2,060,167

BOOKKEEPING AND INVOICING MACHINE

Ernst Breitling, Essen, Germany, assignor, by
mesne assignments, to The National Cash
Register Co., Dayton, Ohio, a corporation of
Maryland

Application December 7, 1929, Serial No. 412,514
In Germany December 13, 1928

24 Claims. (Cl. 235—60)

This invention relates to printing calculating machines of the type having a calculating mechanism so combined with a printing mechanism, that the printing of a text including numerical items can be accompanied by the addition or subtraction of the numerical items, in the calculating mechanism, and can be followed by the printing of the total or difference of the items on the same sheet.

10 One object of the invention is to provide a combined typewriting and calculating machine in which the calculating machine is provided with more than one printing mechanism, at least one of these printing mechanisms being arranged to print upon the paper on the carriage of the typewriting machine. By this arrangement it is possible to obtain, in addition to the figures printed upon the paper on the typewriter carriage, one or more original impression copies from the additional printing mechanism or mechanisms of the calculating machine, whereas heretofore it has only been possible to make copies by taking carbon paper impressions from the single printing mechanism.

15 Another object of the invention is to so combine a typewriter and a calculating machine having a printing mechanism, that the two printing mechanisms print upon the same paper, but at laterally displaced points.

20 Another object is to arrange a carriage moving mechanism for a machine as described in the paragraph above, in which the typewriter controls the movement in one direction and the calculating machine controls the movement in the other direction.

25 Another object is to arrange the carriage moving mechanism controlled by the calculating machine so that it shifts the carriage through a certain number of columns in a certain number of operations, always bringing it to the same end position, but moving it selectively to certain intermediate positions, for instance, to debit or credit columns.

30 Another object is to provide a system of interlocks whereby the operation of the typewriter must precede the operation of the calculating machine, the carriage must be in its lower position for the operation of the calculating machine and cannot be moved out of its lower position while the calculating machine is in operation, the calculating machine printing mechanism can only be operated when the paper carriage is in certain columnar positions and the carriage is held in those positions while the calculating machine is in operation, a certain kind of figure, for

instance, a total, can only be printed in a certain column and the carriage is held against lateral movement during the printing of this figure.

35 Another object is to provide for the line shift of the paper carriage through the operation of the calculating machine, when the paper carriage is in a certain position, for instance, its extreme right position.

Another object is to prevent totals from being printed except when the carriage is in the position in which the line shift is operated by the calculating machine, so that totals from various totalizers can be printed one under another and a grand total or balance of them printed below.

40 Other objects will appear from the following specification in which an example of the invention is described with reference to the accompanying drawings.

In the drawings

Fig. 1 is a front view of a book-keeping and invoicing machine in accordance with this invention.

Fig. 2 is a partial plan view of the machine shown in Fig. 1.

Fig. 3 is a partial side view, with the casing partly broken away.

Fig. 3a is an enlarged view of a part of Fig. 3, with the casing removed.

Fig. 3b is a sectional view of the machine along a row of amount keys.

Fig. 3c is a sectional view of the machine along a row of totalizer keys.

Fig. 3d is a longitudinal sectional view with certain parts in elevation of the totalizer selecting mechanism, along line IIId—III'd of Fig. 3c.

45 Figs. 4 and 5 are respectively a vertical section and a front elevation showing a locking device for the motor or release keys.

Fig. 6 is a vertical section of the carriage moving mechanism controlled by the calculating machine.

Fig. 7 is a horizontal section showing a portion of the carriage moving mechanism controlled by the calculating machine.

Fig. 8 is a side view partly in section of the adjusting means for the carriage moving mechanism.

Fig. 9 is a side view of an interlocking mechanism between the carriage and a control lever.

Figs. 10 to 13 inclusive are sections on the lines 10—10, 11—11, 12—12, and 13—13 of Fig. 6.

Fig. 14 is a partial horizontal section of the transmission means for the calculating machine type which cooperate with the typewriter paper carriage.

Fig. 15 is a bookkeeping voucher as printed by the machine, and

Fig. 16 is a detail view showing the means for controlling a movement of the paper carriage by the typewriter printing mechanism.

The calculating machine of the illustrative embodiment of the invention shown in the drawings is similar to a bookkeeping machine developed from a cash register which is described in the 10 patent to Bornkessel et al., No. 1,896,936, February 7, 1933. In the calculating machine there are eight rows of amount keys 1, two rows of auxiliary totalizer keys 2, a row of five special keys 3, three motor or release keys 4 and a lever 15 5, which determines the kind of operation of the machine, that is, entering amounts, taking totals, etc. The drive of the machine is either by a motor or a crank 6; in the latter case the motor keys 4 serve as release keys. In the machine illustrated, these keys are a "credit" key, for credit items, a "debit" key for debit items and a "clear" key for releasing an idle operation to prepare the machine for taking totals.

The amount set up by the amount keys 1 is 25 additively transmitted to an auxiliary totalizer selected by the totalizer keys 2 and to a special totalizer selected by the special totalizer keys 3. The construction and mode of operation of the differential members for the introduction of the 30 set amounts are known, and are described in detail in the patent to Breitling, No. 1,792,569. For the purpose of a better understanding of the invention, the mechanism is generally outlined in the accompanying drawings. The oscillating 35 movement of shaft 302 (Fig. 3b) effected by the machine drive, causes the tong members 303, 304, by means of reversing drive 305, 306, 307, and 308 to embrace the stem of a depressed key, whereby the differential member 303 executes 40 a movement corresponding to the set value, while the differential member 304 executes a movement corresponding to the complementary value. The actual numerical movement of member 303 is thereby imparted to a driving wheel 308 mounted 45 upon shaft 302, which may engage the individual groups of totalizers 310a, 310b, and 310c through intermediate gears 312 and 313. Subsequent to their selection, one or more of these 50 totalizer groups are coupled with the driving wheel for the purpose of taking up, deducting, or transferring an amount.

The individual groups of totalizers consist of either one single totalizer, which in this case is designated as the calculating, main or special 55 control totalizer, or the group may embrace several individual totalizers such as the auxiliary totalizers, credit and debit totalizers, and sellers' totalizers. The construction of such a group of totalizers may be seen in Figure 3d, this construction being well known in the art, for example in the above mentioned patent to Bornkessel et al., No. 1,896,936, Fig. 15. The selection of the individual totalizer or the selection of the positive or negative side of the calculating 60 totalizer, is executed in known manner by the shifting of the rider axle 314, which is controlled from cam grooved drum 316 by the keys 2 or levers 2a of the totalizer banks 315 under the influence of the differential mechanism for the 65 totalizers, as shown in Fig. 3c. The tong-like differential members for selecting the totalizers operate in the same manner as the amount differential members shown in Fig. 3b. The mode of adding, particularly in the main or calculating 70 totalizer, is explained in the following operations.

If either of the special keys "old credit balance" or "credit" is depressed, the amount is additively transmitted to a main totalizer. If either of the special keys "debit" or "old debit balance" is depressed, the amount is subtractively transmitted to the main totalizer. By depressing the special key "new balance", a suitable adjustment of the kind of operation lever 5 and the depression of one of the motor or release keys 4 "credit" or "debit", the total is taken from the main totalizer. The operations which should take place in a normal bookkeeping transaction are controlled in such a manner, by interlocking devices (not shown), between the various adjusting devices, that upon setting up the old balance and 10 the introduction of the credit or debit, the taking of the new balance must follow. Besides such bookkeeping operations, the total can be taken from one of the totalizers corresponding to keys 2 and 3. This is accomplished by adjusting the lever 5 to the proper position, depressing the proper key 2 or 3 and then the corresponding release key. This total taking operation must be preceded by a clearing operation released by the releasing key "clear".

For every row of keys 1, 2 and 3 there is mounted on the main shaft 7 an adjusting member 8. In entering amounts these adjusting members are set at the beginning of the operation in accordance with the keys depressed in their respective rows; in total taking operations the adjusting members 8 for the amount keys are adjusted according to the positions of the counting wheels of the totalizer from which the total is being taken. The adjustment of the adjusting 35 members 8 is transmitted through worm teeth 9, worm wheels 11, shafts 12, spur wheels 13, 14, shafts 15, spur wheels 16, 17, shafts 18 and spur wheels 19 to a set of rack bars 21 mounted to slide transversely in the frame of the machine. 40 From this set of rack bars the adjustment can be transmitted to as many printing mechanisms as desired.

In the present case there are two printing mechanisms to which the adjustments are transmitted. One printing mechanism is for the control strip on the left side of the machine (Fig. 1) and the other is arranged at the right side of the machine to cooperate with the paper carriage 22 of a typewriting machine 23.

The feed mechanism for the control strip 24 (Fig. 1) is preferably so arranged, in known manner, that the last line which has been printed can be read through an observation opening 25 (Fig. 2), in the position of rest of the machine. 55 In addition to the type for printing on the control strip the amount and the sign of the totalizer, there are type wheels 26, for printing the consecutive number and type wheels 27 for printing the account number. The amount is printed 60 by type wheels 28, which are constantly in positive connection with rack bars 21 through the intermediary of spur wheels 29, 31, telescoped tubes 32, 33, and spur wheels 34, 35.

The adjustment of the account number is 65 accomplished by setting members 38, which are mounted upon a shaft 38' and telescoped tubes 37' (Fig. 1) surrounding this shaft. The setting members 38 are adjusted, in accordance with scale numbers 39 to the values 0 to 9. These 70 adjustments are transmitted to the type wheels 27 through toothed segments 41, vertically sliding double rack bars 42, spur wheels 43, tubes 44, which surround the tubes 38, and spur wheels 45. The drive of the printing mechanism for the 75

control strip 24 is effected through a drive shaft 46 (Fig. 2), which is constantly in engagement with a main drive shaft 49 through bevel wheels 47, 48.

5 On the right of the typewriting machine 23, which prints in the normal manner at its mid-plane indicated by 51, there are seventeen type carriers 50 (Fig. 14), mounted so as to be vertically slidable, by means of pins 52 (Fig. 3a) engaging in slots 53 of the type carriers. The individual types of these type carriers are movably mounted, in the manner common in printing adding machines. The nine type carriers 54 on the left (Fig. 2) are for the amount (see also Fig. 14). 10 The next five type carriers to the right, 55, are for the account number and the three type carriers 56 are for the date of the entry on the voucher. In addition to these there are arranged to the right of type carriers 56 the type wheels 20 57, which are mounted on a common swinging frame. These serve to print the consecutive number on the voucher in the typewriting machine.

The amount type carriers 54 are adjusted by 25 the above mentioned rack bars 21 through the following connections: teeth 58 (Fig. 3a), toothed segments 61 rotatably mounted upon a shaft 36, links 62 (Fig. 3), toothed segments 64 rotatably mounted upon a shaft 63, spur wheels 65, worm wheels 66, shafts 67 and spur wheels 68.

The adjustment of the account number type carriers 55 (Fig. 2) is effected by toothed segments 69 (Fig. 14), which are connected with the setting levers 38 at the left side of the machine by tubes 37, toothed wheels 30, 40 (Fig. 1), and the above mentioned tubes 37'. In a similar manner the type carriers 56 (Fig. 14) for the date of entry on the bookkeeping voucher are connected by toothed segments 71 and tubes 72 40 with knobs 73, directly adjustable by hand.

The type wheels 57 (Fig. 3) for the consecutive number are mounted upon an arm 75 mounted to swing upon a drive shaft 74. The shaft 74 is constantly in positive connection with the main drive shaft 49 through bevel wheels 76, 77 (Fig. 2); a shaft 78 and bevel wheels 79, 81. Between the shaft 74 and the units wheel of the group of type wheels 57 there is a Geneva wheel drive, consisting of a disk 83 (Fig. 3a) fixed upon shaft 74 and having a driving shoulder 82 which engages a spur wheel 84 at each revolution of the disk 83. The spur wheel 84 is geared to the units wheel of the group 57 and advances this wheel by one unit each time it is rotated by the shoulder 82. Between the driving movements the spur wheel 84 is locked by the circular periphery of disk 83 in known manner. The other wheels of the group 57 are connected to each other in the well known manner, so that each revolution of a wheel causes a tenth of a revolution of the wheel on its left.

The type wheels 26 (Fig. 2) for the consecutive number of the control strip are advanced in a similar manner, one unit for each operation of the machine, by the shaft 46, so that the type wheels 26 and 57 always print the same number.

With the type carriers 54 to 56 cooperate separate hammers 86 (Fig. 3a), which are mounted upon a shaft 85 and are normally retained in their position of rest against the action of springs 87 by a retaining bar 89 which lies in front of lugs 88 of the hammers 86. This retaining bar 89 is supported on a frame 92 rockably mounted upon a shaft 91. The frame 92 has a projection 93 which engages a lug 94 in the arm 75 and holds

the latter back against the action of a spring 95 in the outwardly swung position. The frame 92 has also a rigid arm 98 at the end of which is a roller 96 cooperating with a cam disk 97 fixed upon shaft 74. When the shaft 74 is turned the 5 cam disk 97 releases arm 98, so that the hammers 86 and type wheels 57 execute a printing motion under the action of springs 87 and 95, whereby an item is printed upon the voucher on the paper carriage 22. Since the arm 75 swings 10 upon the shaft 74, upon which the driving disk 83 is fastened, the positive connection between the disk 83 and intermediate wheel 84 is maintained during this printing motion. Toward the end of the operation of the machine the frame 92 15 is moved back by the cam disk 97, whereby the hammers 86 and the type wheel carrier 75 are returned to the position shown in Fig. 3.

There is still another locking device for the hammers 86 of the type carriers 55 and 56 for 20 the account number and date, and for the arm 75. This locking device consists of a locking bar 101 engaging behind shoulders 99 of the said hammers 86 and a locking arm 103 engaging behind a shoulder 102 of arm 75. The locking bar 25 101 and arm 103 are on a frame 105 rotatably mounted upon a shaft 104. Another arm 106 of frame 105 is connected with a shiftable rod 107, which has a nose 108 normally engaging the lower end of a locking rod 109, so that the corresponding hammer 86 and the type wheel carrier 75 are normally retained in their positions of rest and an impression of the account number, the consecutive number and the date upon the voucher on the paper carriage is only made when the locking 30 rod 109 is raised. This occurs only upon setting up the old balance. For this purpose the keys "old debit balance" and "old credit balance" have pins 111 which engage inclined faces 112 of a 35 displaceable key slide 110, to which the locking 40 rod 109 is connected.

This arrangement is used in connection with the form of voucher shown in Fig. 15. This figure shows the voucher as it appears when printed by the typewriter and the set of type 54 to 57. 45 The columns marked 113 are printed in a normal way by the typewriter before the beginning of the calculating machine operation for the same transaction. The columns 113 are for the number of the voucher, the description of the item, 50 the date of the item and the sign of the totalizers. During the printing by the typewriter the voucher on the paper carriage is moved from space to space, under the action of a spring (not shown) within the spool 300 upon which is wound 55 a cord 301 connected to the carriage, the motion of the carriage being controlled by an escape mechanism 302, of conventional form, operated by the type bars 303 of the typewriter. In the first operation of the calculating machine which 60 follows, in which the old balance is set up, the type carriers 54 to 57 print in the columns 114 (Fig. 15). In these columns there appear beside the old balance, the account number, the date of entry on the voucher and the consecutive 65 number. In the two operations which follow, there are printed in columns 115 or 116 the debit or credit amount, and, in column 117, the new balance, all without the account number, the date and the consecutive number. This is so because in these operations neither "old balance" 70 key is depressed, so that rod 109 (Fig. 3) remains in its locking position and the hammers 86 cooperating with type carriers 55 and 56 are locked by the locking bar 101, while the arm 75 is re- 75

tained in position of rest by the locking arm 103. When the last sign is printed in the totalizer sign column, the column "old balance" is to the left of type carriers 54, so that the paper carriage must be moved one column to the right before the printing, which occurs during the first operation.

If a debit amount is to be entered on the second operation, the carriage must be moved, before 10 the printing, one column to the right. If it is a credit amount, the carriage movement is two columns, in the same direction. Upon the third operation (new balance) if the preceding operation was a debit transaction, the movement of 15 the carriage must be a two-column one, while if the preceding operation was a credit transaction, the necessary movement is one column. In any case there must be upon depression of an "old balance" key and the "debit" key, a carriage 20 movement of one space, and upon depression of the "credit" key, a movement of two spaces.

For moving the paper carriage 22 from left to right, that is, against the action of the carriage spring, the paper carriage is positively coupled 25 with the drive of the calculating machine. The paper carriage frame 119 is mounted on ball-bearings 120 (Fig. 6) on a trackway 118, which can be shifted vertically to change from small to capital letters. A rack bar 121 is connected with 30 the carriage frame 119 in such a manner that the rack bar is forced to follow the lateral motions of the carriage, but not its vertical shifting. The rack bar 121 is connected through a pinion 122 journalled on the machine frame, with a toothed 35 wheel 124 fixed upon a shaft 123 rotatably mounted in the frame of the machine. On the shaft 123 is an adjustable transmission member 125 having an extended hub 127 provided with slots 128 (Fig. 7) through which project the pin 40 128. The transmission member is therefore longitudinally adjustable but not rotatable, with respect to the shaft 123. The transmission member 125 has three different zones of teeth. In the one on the left (Fig. 6) are four teeth 131a, b, c 45 and d (Fig. 13); in the middle zone are three teeth 132a, b, and c (Fig. 11); in the right hand zone there is one tooth 133 (Fig. 10). The teeth 131 cooperate selectively with driving disks 135, 136, in the manner of a Geneva wheel. The driving 50 disks 135, 136 are fixed upon a drive shaft 134 (Fig. 6), to which is imparted, by the main drive shaft 49, one rotation, at each operation of the machine. The driving disks 135, 136 have recesses 137 (Fig. 13), which are turned toward the 55 teeth 131, in the position of rest of the machine, so that the paper carriage can move freely upon operation of the typewriter keys. When the shaft 134 is set in rotation during an operation of the calculating machine, the peripheral surface 138 of disk 135, or 136, moves into the space between the teeth 131 and locks the transmission member 125, and thereby the paper carriage, in their positions of rest, until a driving pocket 60 comes under the tooth 131, which, at that time, is projecting downwardly to the right. At that moment the transmission member is rotated 90°, by the driving pocket and another device to be presently described, and the paper carriage is thereby moved for the space of one column. The 65 driving disk 135 is provided with a single driving pocket 139 and the driving disk 136 has two driving pockets 141, 142. In order to turn the teeth 131 into the driving pockets 139, 141, 142, two teeth 144 and 145 (Figs. 6, 10 to 12) are provided 70 on the driving body 143 secured to shaft 134 that

carries the disks 135, 136. The tooth 144 causes the engagement of teeth 131 with the two driving pockets 139, 141, while the tooth 145 causes the engagement of the teeth 131 with the driving pocket 142. In performing these functions, the 5 two teeth 144 and 145 cooperate with the three teeth 132 and the single tooth 133 in the manner described in detail herebelow.

For the purpose of shifting the transmission member 125 laterally for engagement with either 10 disk 135 or 136, the transmission member is provided with a circular groove 146 (Figs. 6, 7, 8) in which is engaged a fork 147, which is secured to a bushing 149 loosely mounted upon a shaft 148 rotatably mounted in the frame of the machine and secured against longitudinal motion. Upon shaft 148 is fixed a drum 152 having a cam slot 150 in which engages a roller 151 mounted upon the fork 147. The drum 152 has an ear, 152' (Fig. 8) connected by a pin 153 with a thrust 20 rod 154, which is supported at its mid-point by a link 155. The free end of thrust rod 154 is provided with an open slot 156 adapted to engage a pin 157 mounted upon a driving arm 158, which is given a to and fro swinging motion at each operation of the machine. As shown in Fig. 3, the upper end of link 155 is connected to a key slide 159. The key slide has inclined surfaces 160, 170 lying in the path of the pins 111 of the keys "credit" and "new balance". When either of 30 these keys is depressed, the slide 159 moves upward and draws with it the thrust rod 154 so that the slot 156 (Fig. 8) comes out of engagement with pin 157. In its position of rest the drum 152 lies in the angular position shown in 35 Fig. 8, so that the transmission member 125 (Fig. 6) is in its right end position (Fig. 6) and the teeth 131 cooperate with the driving disk 136, while teeth 132 cooperate with teeth 144 and 145 and tooth 133 with tooth 145. The drum 152 and transmission member 125 remain in this position whenever either of the keys "credit" or "new balance" has been depressed, in setting the machine.

If one of the other special keys 3 has been depressed, the thrust rod 154 (Fig. 8) remains in engagement with pin 157 and, at the beginning of the operation of the machine, is moved to the left, whereby the transmission member 125 is adjusted to the left end position (Fig. 6), in which its teeth 131 cooperate with driving disk 135, and its teeth 132 and tooth 133 with tooth 144.

During one complete bookkeeping transaction the movement of the paper carriage through the transmission member 125 takes place in the following manner: after the columns 113 (Fig. 15) of the voucher have been written by the typewriter machine keys, an operation of the calculating machine for introducing the old balance 60 is released. At the conclusion of a typewritten entry in column 113 the carriage is in a position, in relation to the type carriers 55 to 57, in which the column 114 is one column space to the left (Fig. 2) of the proper position to receive entries from the type carriers 55 to 57. Since, in this case, neither of the keys "credit" and "new balance" is depressed, the transmission member 125 is adjusted to the position shown in Fig. 6. In combination with the tooth 144 (Fig. 11), which engages the tooth 132a, the driving disk 135, engaging with the tooth 131a, causes a quarter revolution of the transmission member 125 and thereby a displacement of the paper carriage for the space of one column, so that the type carriers 55 to 57 stand opposite the columns 114 (Fig. 15). 75

If the "debit" key is depressed, in the next operation, the transmission member 125 again assumes its left end position. The tooth 144 (Fig. 11) now works upon the tooth 132b, which 5 has assumed the downwardly directed position, at the beginning of the second operation, so that the driving disk 135, in cooperation with tooth 131b, again causes a quarter revolution of the transmission member 125 and a further movement of the paper carriage for the space of one column.

If, on the other hand, the "credit" key had been depressed, the transmission member 125 would have been left in its right end position. 10 In this case, after the tooth 144 (Fig. 11) had engaged the tooth 132b and caused the engagement of tooth 131b (Fig. 13) with the driving pocket 141 of driving disk 136 and the transmission member 125 had been turned a quarter revolution, the tooth 145 (Fig. 11) would have engaged the tooth 132c of transmission member 125 and caused the engagement of tooth 131c (Fig. 13) with the second driving pocket 142 of the driving disk 136, so that the paper carriage 15 would have been moved for the space of a second column and the credit column 116 (Fig. 15) of the voucher would have been adjusted to the position opposite the type carriers 54.

Since the "new balance" key is depressed in the third operation of the machine, the transmission member 125 remains in its right end position. If the preceding operation was a debit transaction, the tooth 132c (Fig. 11) projects downward, but if the preceding operation was a credit transaction, there is no tooth 132 projecting downwardly from the transmission member 125. However, in the latter case, the tooth 133 (Fig. 10) projects downward. Assuming the preceding operation to have been a debit transaction, the teeth 144 and 145 successively engage the teeth 132c and 133 (Figs. 11 and 10) and cause, in cooperation with the driving disk 136, the turning of the transmission member 125 for two quarter revolutions. If the preceding operation was a credit transaction, the transmission member 125 is turned a quarter revolution, by the engagement of tooth 145 with tooth 133 (Fig. 10) and tooth 131d (Fig. 13) in driving pocket 142. In either case, the "new balance" column arrives opposite the type carriers 54. It will be seen that the total movement toward the right of the paper carriage caused by the transmission member 125 is composed of four units. By this movement the first space of the first column at the left of the voucher (voucher number) again arrives at the printing point 51 of the typewriter (Fig. 2). Naturally the device can be so arranged that when the column "tot." (Fig. 15) has been printed by the typewriting machine, the columns 114 stand directly opposite the type carriers 54 to 57, in which case the paper carriage is not moved during an "old balance" operation. This can be accomplished in a simple manner, for instance, by making the transmission member 125 with three equi-spaced teeth instead of four and by disconnecting the shaft 134 from the driving mechanism in "old balance" operations.

A brief summary of the carriage movements 70 for a series of operations, including "debit" and "credit" entries, follows.

The first operation of any series is to set up and enter the "old balance". After the typewritten entry is completed, the carriage stops 75 in a position one column to the left of the "old

balance" position. During the first part of the "old balance" operation the tooth 144 strikes tooth 132a to shift the carriage one step, whereupon the "old balance" is printed. Depression of the "debit" key shifts the driving member 125 10 to the position shown in Fig. 6, and a subsequent operation of the machine causes tooth 144 to engage tooth 132b to shift the carriage another columnar space, whereupon the debit amount is printed. The next operation is the "new balance" operation, and depression of the "new balance" key controls the shifting of the driving member 125 to position the member 125 in position to cause tooth 132c to be engaged by tooth 144 and the tooth 133 to be engaged by tooth 145 15 to give the carriage two steps of movement.

The following steps are given the carriage during a series of operations, including a "credit" entry. The first operation consists of an "old balance" operation, during which the member 20 125 is in the position shown in Fig. 6, and during which the tooth 144 engages tooth 132a to move the carriage one columnar position to receive the "old balance". For the next operation the "credit" key is depressed, whereupon the member 25 125 shifts to the right (Fig. 6) to bring the teeth 132b and 132c in line with teeth 144 and 145. Therefore, during the machine operation, the teeth 144 and 145 successively engage teeth 30 132b and 132c to shift the carriage two columnar spaces. When the "new balance" key is depressed to complete the series of operations, the member 125 remains in the right hand position, and during the machine operation, the tooth 144 has no effect on tooth 132 because no tooth thereon 35 is in position to be engaged thereby, but the tooth 145 will engage the tooth 133 to shift the carriage one columnar space from the "credit" column to the "new balance" column.

When the paper carriage is moved back into 40 its right end position, at the end of a "new balance" operation, an arm 161 (Fig. 3) of a bell crank lever 163 arrives under a lever 164 pivoted on the frame of the machine. The lever 164 is given a swinging movement, at each operation 45 of the machine, by means of a roller 165 (Fig. 2) mounted on a thrust rod 165a and cooperating with a cam disk 166 on drive shaft 49. The thrust rod 165a is connected to lever 164 through bell crank lever 165b and thrust rod 165c. The 50 bell crank lever 163 has a pawl 162 engaging a ratchet wheel 167 of the paper roller 22. When the paper carriage is in its right end position, so that lever 164 lies over bell crank lever 163, the motion of lever 164 received from the cam 166 55 causes the advance of the paper roller for the space of one line. It will be noted that the automatic line shift is arranged to take place in the column in which the totals are printed, so that a plurality of totals from various totalizers can be 60 printed one under another and, if desired, added or subtracted in any suitable way to obtain a grand total or balance.

A number of interlocks between the paper carriage and the setting mechanism are provided, 65 by means of which the adjustment of the paper carriage to the columns corresponding to the various transactions is enforced. In order to prevent the type carriers 54 to 57 from printing, when the paper carriage is raised to the capital 70 letter position and to prevent the paper carriage from being raised to the capital letter position during an operation of the calculating machine, a locking rod 176 is provided. This locking rod 176 is guided in a partition 175 of the frame of 75

the machine and is connected to a lever 174 pivotally mounted on a stationary shaft 173. A second arm of lever 174 is connected by a rod 172 to a key slide 171 having inclined surfaces 169 with which cooperate pins 168 (Fig. 4) on the motor keys "credit" and "debit". If the paper carriage is in its raised capital letter position, the rear face 171 of the carriage frame 119 lies in front of the free end of rod 176, so that the motor keys "debit" and "credit" are locked. On the other hand, when the depression of one of these keys causes the free end of rod 176 to move over the upper surface 178 of the paper carriage, the shifting of the typewriter to the capital letter position is no longer possible, so long as these keys remain depressed.

When the shaft 134 (Fig. 13) is in its position of rest, the transmission member 128 is released; therefore the paper carriage can be moved to any desired position. In order to make the printing of the type carriers 54 (Fig. 2) always take place exactly in the prescribed columns of the voucher (Fig. 15), the rack bar 121 (Figs. 6 and 4) is provided with a locking flange 179, which cooperates with a locking lever 181 mounted on the shaft 173 (Fig. 4). The locking lever 181 is positively connected by a link 182 to a lever 184 mounted on a stationary shaft 183. The lever 184 is connected by a rod 185 and a lever 186 with a key slide 187 having inclined surfaces 188, 189 cooperating with the "credit" and "debit" motor or release keys. The locking flange 179 has recesses 191 (Fig. 2), which stand exactly above the free end of lever 181 when the paper carriage is in the various columnar positions. Therefore it is only in these positions of the paper carriage that a motor or release key "debit" or "credit" can be depressed. When either of these keys is depressed, the free end of lever 181 enters the corresponding recess 191 (Fig. 2), whereby the paper carriage is temporarily secured against lateral motion. In combination with these interlocks a device is provided, by means of which the release of the calculating machine is prevented, until the columns 113 (Fig. 15) have been printed by the typewriter. For this purpose the lever 184 (Fig. 4) is provided on its free end with a tilttable pawl 192, which cooperates with a projection 193 (Figs. 4, 5) of an adjustable lever 195 pivoted by a pin 194 upon the partition 175. The lever 195 has a finger 196 (Fig. 5) cooperating with two lugs 197, 198 on the locking flange 179. The adjustable lever 195 is yieldably held in one of two angular positions by means of a spring influenced click 199 (Fig. 5) having a nose 201 adapted to engage either of two notches 202 and 203 of the lever 195.

In the condition of rest of the machine lever 195 is in the position shown in Fig. 5, where the projection 193 lies over pawl 192, thereby locking the lever 184 and, through rod 185, lever 186 and key slide 187, prevents the depression of the "debit" and "credit" motor or release keys. As soon as the paper carriage reaches its left end position, through the operation of printing the columns 113 (Fig. 15), the lug 198 (Fig. 5) strikes finger 196 and swings lever 195 into its other angular position, in which the projection 193 lies out of the path of pawl 192. The depression of a "credit" or "debit" motor or release key can therefore take place without obstruction by the projection 193; at the same time the locking lever 181 enters the recess 191 furthest to the right (Fig. 2). As soon as the paper carriage arrives in its right end position, as a result of its stepwise backward movement, the lug 197 (Fig. 5) strikes finger

196 from the left, so that projection 193 is again moved into locking position.

If a total or sub-total is to be taken from any of the totalizers corresponding to the keys 2 and 3 (Fig. 1), this must be printed with the paper carriage in the "new balance" position. To insure such an alinement there is rigidly connected with the toothed wheel 124 (Figs. 6 and 9) a locking disk 204 having a recess 209. When the carriage is in the "new balance" position, this recess is turned toward a locking finger 205 on an arm 208 mounted on a shaft 206 and under the influence of a spring 207. To the shaft 206 is fastened a second arm 211 having at its end a roller 212. The spring 207 holds the roller 212 against the shouldered lower surface 213, 214 of a slidable bar 215 positively connected with the lever 5 (Fig. 1). As long as the lever 5 is in its position of rest, the finger 205 is held out of contact with the locking disk 204, but when the lever 5 is moved out of its position of rest, for total taking, the finger 205 enters the recess 209, if the paper carriage is in its right end position, the surface 214 running onto the roller 212. Thereby the paper carriage is held in its starting position, during the operation of taking a total from the selected totalizer.

As described above, the motor or release keys "debit" and "credit" are locked by the lever 195 (Fig. 4), when the carriage is in the "new balance" position. For the purpose of removing this locked condition for total taking, there is positively connected with the lever 5 a cam disk 216 (Fig. 4), with which cooperates a lever 218 situated in the plane of the key slide 187. When the lever 5 is adjusted for total taking, the cam disk 216 is turned to the left, whereby the key slide 187 is moved down, so that its inclined surfaces go past the pins 168. The motor or release keys "credit" and "debit" can then be depressed irrespective of the locking position of lever 195.

As previously stated, every total taking operation must be preceded by a clearing operation. By means of a device, not shown, the lever 5 can only be moved out of its position of rest when there has just been a clearing operation. In order that the motor or release key "clear" (Fig. 4) shall only be released for depression when the paper carriage is in its "new balance" position, this key has a pin 217 engaging an inclined surface 218 of a key slide 219, which is connected by a rod 221 with a lever 222 pivoted upon the shaft 173. The lever 222 reaches under the locking flange 179 (Figs. 4 and 2) and only permits the "clear" key to be depressed when a notch 223 in the locking flange 179 is above its free end. This is only the case when the paper carriage is in its "new balance" position.

I claim:

1. In a machine of the class described, the combination with a typewriter having a movable paper carriage and a printing mechanism, of a calculating machine having a printing mechanism, said two printing mechanisms being arranged to print upon a paper on said paper carriage at laterally displaced points, means controlled by said typewriter printing mechanism for imparting a single space movement to said carriage in one direction, and means controlled by said calculating machine for imparting a step-by-step movement to said carriage in the other direction.

2. A machine as specified in claim 1, in which the means controlled by said calculating machine for imparting a step-by-step movement to

5 said carriage comprises a driving member having a definite movement for each operation of the calculating machine, and adjustable transmission means between said driving member and 5 said carriage, adapted to impart a movement of one or more columns to said carriage.

3. In a machine of the class described, the combination with a typewriter having a movable paper carriage and a printing mechanism, of a 10 calculating machine having a printing mechanism, said two printing mechanisms being arranged to print upon a paper on said paper carriage at laterally displaced points, means whereby the movement of said paper carriage in one 15 direction is controlled by said typewriter printing mechanism, and means controlled by said calculating machine for imparting to said carriage a tabular return movement, said last mentioned means being adapted to move said carriage 20 during a certain number of operations of said calculating machine through a number of columns greater than the number of operations of said calculating machine, the total movement being always the same, but the movement caused 25 by the individual operations of the calculating machine being variable.

4. In a machine of the class described, the combination with a typewriter having a movable paper carriage and a printing mechanism, of a 30 calculating machine having a printing mechanism, said two printing mechanisms being arranged to print upon a paper on said paper carriage at laterally displaced points, means whereby the movement of said paper carriage in one 35 direction is controlled by said typewriter printing mechanism, and means controlled by said calculating machine for imparting to said carriage a tabular return movement, said last mentioned means being adapted to move said carriage 40 through three columns during two successive operations of said calculating machine, and adjustable means for causing a two column movement of said carriage to take place at the first of said operations and a single column 45 movement at the second operation, or a single column movement to take place at the first of said operations and a double column movement at the second.

5. In a machine of the class described, the combination with a typewriter having a movable paper carriage and a printing mechanism, of a calculating machine having a printing mechanism, said two printing mechanisms being arranged to print upon a paper on said paper carriage at laterally displaced points, means whereby the movement of said paper carriage in one direction is controlled by said typewriter printing mechanism, and means controlled by said calculating machine for imparting to said carriage 55 a tabular return movement equal to four columns during three successive operations of said calculating machine, said last mentioned means being adapted always to adjust said carriage in the first and last of said columns and to selectively adjust said carriage in the two intermediate columns.

6. In a machine of the class described, the combination with a typewriter having a movable paper carriage and a printing mechanism, of a 60 calculating machine having a printing mechanism, said two printing mechanisms being arranged to print upon a paper on said paper carriage at laterally displaced points, means whereby the movement of said paper carriage in one 65 direction is controlled by said typewriter print-

ing mechanism, and means controlled by said calculating machine for imparting to said carriage a tabular return movement equal to four columns during three successive operations of said calculating machine, said last mentioned 5 means comprising a Geneva gear consisting of a transmission member positively connected to said carriage and a driving member positively connected to the driving means of said calculating machine, said transmission and driving members 10 having two sets of driving connections, one adapted to cause a one column movement of said carriage and the other adapted to cause a two column movement of said carriage, manipulative means for determining the kind of operation 15 of said calculating machine, means for relatively shifting said transmission member and driving member to couple one or the other of said sets of driving connections, and connections whereby said shifting means is controlled by said manipulative means.

7. In a machine of the class described, the combination with a typewriter having a movable paper carriage and a printing mechanism, of a calculating machine having a printing mechanism, said two printing mechanisms being arranged to print upon a paper on said paper carriage at laterally displaced points, means whereby the movement of said paper carriage in one direction is controlled by said typewriter printing 25 mechanism, and means controlled by said calculating machine for imparting to said carriage a tabular return movement equal to four columns during three successive operations of said calculating machine, said last mentioned means 30 comprising a Geneva gear consisting of a transmission member positively connected to said carriage and a driving member positively connected to the driving means of said calculating machine, said transmission and driving members having 35 two sets of driving connections, one adapted to cause a one column movement of said carriage and the other adapted to cause a two column movement of said carriage, means for selectively coupling said one column movement driving connections for the first two of said three successive operations and the two column movement driving connections for the third of said operations, or said one column movement driving connections 40 for the first of said operations and said two column movement driving connections for the last two of said operations, said two column movement driving connections being so constructed as to impart only a one column movement to said carriage upon the third of said operations when 45 the second of said operations is accompanied by a two column movement.

8. A machine as specified in claim 3 in which said means controlled by said calculating machine for imparting a return movement to said carriage 50 comprises a Geneva wheel gear consisting of a rotatable transmission member positively geared to said carriage so as to make one complete rotation during the total movement of said carriage, a driving member geared to the driving means 55 of said calculating machine so as to make one complete rotation for each operation of said calculating machine, and driving connections between said driving member and said transmission member adapted to impart to said transmission member a partial rotation of variable extent for each rotation of said driving member.

9. In a machine of the class described, the combination with a typewriter having a movable paper carriage and a printing mechanism, of a 75

- calculating machine having a printing mechanism, said two printing mechanisms being arranged to print upon a paper on said paper carriage at laterally displaced points, means whereby 5 by the movement of said paper carriage in one direction is controlled by said typewriter printing mechanism, and means controlled by said calculating machine for imparting to said carriage a tabular return movement equal to four columns 10 during three successive operations of said calculating machine, said last mentioned means comprising a Geneva wheel gear consisting of a transmission member positively connected to said carriage and a driving member positively connected to the driving means of said calculating machine, said transmission and driving members having two sets of driving connections, one adapted to cause a one column movement of said carriage and the other adapted to cause a two column 15 movement of said carriage, manipulative means for determining the kind of operation of said calculating machine, a cam for relatively shifting said transmission member and driving member to couple one or the other of said sets of driving 20 connections, a swinging member driven by the driving means of said calculating machine, disengageable connections between said swinging member and said cam, and means whereby the engagement of said last mentioned connections is 25 controlled by said manipulative means.
10. In a tabulating machine, a movable paper carriage, two printing mechanisms adapted to print at laterally displaced points on a paper on said paper carriage, means for imparting a step-by-step movement in one direction to said carriage upon operation of one of said printing mechanisms, and means for imparting a step-by-step movement in the other direction to said carriage upon operation of the other of said printing 40 mechanisms.
11. In a machine of the class described, the combination with a typewriter having a movable paper carriage and a printing mechanism, of a calculating machine having a printing mechanism, said two printing mechanisms being arranged to print upon a paper on said paper carriage at laterally displaced points, means whereby the movement of said paper carriage toward the left is controlled by said typewriter printing mechanism, means whereby the movement of said paper carriage toward the right is controlled by said calculating machine, and means preventing the operation of said calculating machine until said carriage is moved to its extreme left position.
12. A machine as recited in claim 11, in which said means for preventing operation of said calculating machine until said carriage is moved to its extreme left position comprises a pivoted lug, means yieldingly holding said lug in either of two positions, connections whereby a releasing key of said calculating machine is locked when said lug is in one position and released when said lug is in the other position, and means whereby the position of said lug is controlled by the movement of said carriage to its two end positions.
13. In a machine of the class described, the combination with a typewriter having a paper carriage and a printing mechanism, of a calculating machine having a printing mechanism, said two printing mechanisms being arranged to print upon a paper on said paper carriage at laterally displaced points, means for raising said carriage for printing capital letters, a releasing key for said calculating machine and means preventing

depression of said releasing key when said carriage is raised and preventing said carriage from being raised when said releasing key has been depressed.

14. In a machine of the class described, the combination with a typewriter having a movable paper carriage and a printing mechanism, of a calculating machine having a printing mechanism, said two printing mechanisms being arranged to print upon a paper on said paper carriage at laterally displaced points, means whereby the movement of said paper carriage toward the left is controlled by said typewriter printing mechanism, means whereby the movement of said paper carriage toward the right is controlled by said calculating machine, releasing keys for said calculating machine, locking means for said releasing keys, means whereby said locking means is controlled by said carriage in such a manner as to lock said releasing keys upon movement of said carriage into its extreme right position and to release said releasing keys upon movement of said carriage into its extreme left position, a total taking lever, and means operated by said total taking lever for disabling said locking means.

15. In a machine of the class described, the combination with a typewriter having a movable paper carriage and a printing mechanism, of a calculating machine having a printing mechanism, said two printing mechanisms being arranged to print upon a paper on said paper carriage at laterally displaced points, means whereby the movement of said paper carriage in one direction is controlled by said typewriter printing mechanism, and means whereby movement of said paper carriage in the opposite direction is controlled by said calculating machine, said last mentioned means comprising a Geneva wheel gear by which the driving means of the calculating machine is positively connected to the carriage.

16. In a machine of the class described, the combination with a typewriter having a movable paper carriage and a printing mechanism, of a calculating machine having a printing mechanism, said two printing mechanisms being arranged to print upon a paper on said paper carriage at laterally displaced points, means whereby the movement of said paper carriage in one direction is controlled by said typewriter printing mechanism, and means whereby movement of said paper carriage in the opposite direction is controlled by said calculating machine, said last mentioned means comprising a Geneva wheel gear consisting of a transmission member positively geared to said carriage, and a driving member positively driven by the driving means of said calculating machine, driving disks on said driving member, teeth on said transmission member cooperating with said driving disks, said driving disks having recesses permitting free rotation of said transmission member when said driving disks are in position of rest.

17. In a calculating machine, a printing mechanism, a laterally movable paper carriage co-ordinated with said printing mechanism, and means for preventing operation of the calculating machine except when said carriage is in certain positions, said means comprising a flange on said carriage having recesses corresponding to said certain positions, and a pivoted arm having one end arranged to be positively actuated by a releasing key of the calculating machine, the other end of said arm cooperating with said

- flange and permitting said arm to tilt only when aligned with one of said recesses.
18. In a calculating machine, a printing mechanism, a laterally movable carriage, means for adjusting said carriage to various positions for causing said printing mechanism to print in columns, means for setting the machine to print totals, means to prevent operation of said setting means unless said carriage is in a certain position, line spacing means, and means for automatically actuating said line-spacing means only when said carriage is in said certain position.
19. In a tabulating machine, a movable paper carriage, two printing mechanisms adapted to print at laterally displaced points on a paper on said paper carriage, means for imparting a step-by-step movement in one direction to said carriage upon operation of one of said printing mechanisms, means for imparting a step-by-step movement in the other direction to said carriage upon operation of the other of said printing mechanisms, and means preventing operation of said last mentioned printing mechanism until said carriage moves to a limit position in the direction controlled by said first mentioned printing mechanism.
20. In a tabulating machine, a movable paper carriage, two printing mechanisms adapted to print at laterally displaced points on a paper on said paper carriage, means for imparting a step-by-step movement in one direction to said carriage upon operation of one of said printing mechanisms, means for imparting a step-by-step movement in the other direction to said carriage upon operation of a second printing mechanism, and means preventing operation of said last mentioned printing mechanism until said carriage moves to a limit position in the direction controlled by said first mentioned printing mechanism, said last mentioned means comprising a pivoted lug, means yieldingly holding said lug in either of two positions, connections whereby the operation of said second printing mechanism is prevented when said lug is in one position, but not when said lug is in the other position, and means whereby the position of said lug is controlled by the movement of said carriage to its two end positions.
21. In a calculating machine, a printing mechanism, a laterally movable paper carriage coordinated with said printing mechanism designed to have amounts printed in several columns of the paper, means for setting said calculating machine to print totals in one of said columns, and means controlled by said carriage for preventing the adjustment of said setting means except when said carriage is in a certain position corresponding to the column containing totals, said last mentioned means being so constructed and arranged as to prevent lateral movement of said carriage when said setting means has been adjusted.
22. In a calculating machine, a printing mechanism comprising a plurality of groups of types, actuating means for said groups of types, a laterally movable paper carriage coordinated with said printing mechanism, manipulative means comprising several types of keys for setting the machine for several kinds of operations, means controlled by the position of the carriage for selectively releasing said several types of keys, and releasing means for said actuating means variably controlled by said several types of keys whereby said several groups of types are actuated differently for the several kinds of operation of the machine, and in accordance with the position of the carriage.
23. In a calculating machine, a printing mechanism comprising a plurality of groups of types, actuating means for said groups of types, a laterally movable paper carriage coordinated with said printing mechanism, manipulative means comprising several types of keys for setting the machine for several kinds of operations, means controlled by the position of the carriage for selectively releasing said several types of keys, releasing means for all of said actuating means, additional releasing means for the actuating means of certain of said groups for effecting a separate control thereof, both of said releasing means being controlled by said several types of keys whereby said several groups of types are actuated differently for the several kinds of operation of the machine and in accordance with the position of the carriage.
24. In a calculating machine, a printing mechanism, a laterally movable paper carriage coordinated with said printing mechanism designed to have amounts printed in several columns of the paper, manipulative means for setting the machine for entering amounts therein, manipulative means for setting the machine for total-taking operations, locking means controlled by said carriage for preventing the operation of said first-mentioned manipulative means when said printing mechanism is not aligned with said columns, and additional locking means controlled by said carriage for preventing the operation of said last-mentioned manipulative means when said printing mechanism is not aligned with that one of said columns which is designed to contain the amounts obtained during said total-taking operations.

ERNST BRETTING.
